DESIGN FOR A CONTAINER CAP

Sidney Kessler, Brooklyn, N. Y., assignor to American Spirits, Inc., New York, N. Y., a corporation of Maryland

Application February 13, 1935, Serial No. 55,381

Term of patent 3½ years

To all whom it may concern:

Be it known that I, Sidney Kessler, a citizen of the United States, and a resident of Brooklyn, county of Kings, and State of New York, have invented a new, original, and ornamental Design for a Container Cap, of which the following is a specification, reference being had to the accompanying drawing, forming part thereof.

I claim:

The ornamental design for a container cap, as shown.

SIDNEY KESSLER.
